US00D586688S

(12) **United States Design Patent**
Bromley et al.

(10) **Patent No.:** **US D586,688 S**
(45) **Date of Patent:** **** Feb. 17, 2009**

(54) **INDOOR GARDENING APPLIANCE**

(75) Inventors: **Robert Bromley**, Centennial, CO (US);
Robert E. Wainwright, Longmont, CO (US); **W. Michael Bissonnette**, Boulder, CO (US)

(73) Assignee: **AeroGrow International, Inc.**, Boulder, CO (US)

(**) Term: **14 Years**

(21) Appl. No.: **29/235,880**

(22) Filed: **Aug. 8, 2005**

(51) **LOC (9) Cl. 11-02**

(52) **U.S. Cl. D11/144**

(58) **Field of Classification Search** D6/403-405;
D7/561; D11/143-146, 152-154; D26/9,
D26/16, 19; D99/19, 23, 27; 47/32.7, 33,
47/39, 41.01, 41.1, 41.11, 44-47, 65.5, 65.8,
47/66.5-66.7, 67, 69, 71

See application file for complete search history.

(57) **CLAIM**

The ornamental design for an indoor gardening appliance, as shown and described.

DESCRIPTION

FIG. 1 is a front elevation view of an indoor gardening appliance showing our new design;

FIG. 2 is a top, front, right side perspective view thereof;

FIG. 3 is a back elevation view thereof;

FIG. 4 is a top, back, left side perspective view thereof; and,

FIG. 5 is a top plan view thereof.

The bottom of the indoor gardening appliance is flat and unadorned.
